Attorney

UNITED STATES PATENT OFFICE.

BERNHARD E. FERNOW, JR., OF MILWAUKEE, WISCONSIN, ASSIGNOR TO THE CUTLER-HAMMER MFG. CO., OF MILWAUKEE, WISCONSIN, A CORPORATION OF WISCONSIN.

BRAKE.

Application filed July 2, 1921. Serial No. 482,070.

To all whom it may concern:

Be it known that I, BERNHARD E. FERNOW, Jr., a citizen of the United States, residing at Milwaukee, in the county of Milwaukee and State of Wisconsin, have invented new and useful Improvements in Brakes, of which the following is a full, clear, concise, and exact description, reference being had to the accompanying drawing, forming a part of this specification.

This invention relates to improvements in brakes and more particularly to electro-magnetic brakes of the drum type.

Such brakes are commonly provided with opposed brake shoes having a spring pressure device associated therewith for setting the same and an electro-magnet for effecting release thereof. The field member of the electro-magnet is usually fixed to a stationary support while the armature member thereof is usually connected to the brake shoes through the medium of a toggle. In practice it has been found exceedingly difficult to maintain the parts of the brake in proper adjustment since a slight off centering of the drum with respect to the shoes prevents equalization of the setting pressure on the shoes and also prevents sealing of the armature with the field member upon release of the brake.

The present invention has among its objects to provide an electro-magnetic brake of the drum type having its parts arranged so that equalization of the setting pressure on the shoes and sealing of the armature member with the field member are not dependent upon exact centering of the drum with respect to the shoes.

Another object is to provide a rugged, compact and efficient brake of the aforesaid character having its parts arranged to materially reduce the overhead space required by the brake.

Another object is to simplify and reduce the number of parts in the operating mechanism of the brake.

Various other objects and advantages of the invention will hereinafter appear.

The accompanying drawing illustrates a brake embodying the invention in one form and the same will now be described, it being understood that the brake illustrated is susceptible of various modifications without

departing from the scope of the appended claim.

In the drawing,

Fig. 1 is a side elevational view of the brake;

Fig. 2 is an end view thereof; and,

Fig. 3 is a sectional view on line 3—3 of Fig. 1.

Referring to the drawing the same illustrates a drum 1 to be secured to the motor or other device to be braked, opposed brake shoes 2 and 3 to frictionally engage said drum and levers 4 and 5 supporting said shoes respectively. Each of said levers comprises a pair of parallel side arms arranged on opposite sides of a base 6, the former lever having its lower end pivotally secured to said base by a pin 7 and the latter having its lower end pivotally secured thereto by a pin 8. Brake shoes 2 and 3 are arranged between the arms of their respective levers and are pivotally secured thereto by pins 9 and 10 respectively and each of said levers is provided with a connecting web 11 carrying an adjustable stop 12 for the lower end of its respective shoe.

Shoes 2 and 3 are normally held against drum 1 under action of a spring 13, said spring being operatively connected to levers 4 and 5 through the medium of rods 14 and 15 and yoke member 16 between said rods. Rod 15 has its left end slidably mounted within a block 17 pivotally secured at 18 to the upper end of lever 4 and said rod is adjustable within said block by nuts 19 arranged on opposite sides of the latter. Rod 14 is slidable within an opening in a connecting web 20 located adjacent the upper end of lever 5 and spring 13 is held under compression between washers 21 and 22, the former washer being slidable on rod 14, said web and the latter being adjustable on rod 14 by nuts 23.

The brake releasing means includes a field member 24 provided with a winding 25 and an armature member 26 to be attracted by said winding. Field member 24 is made up of U-shaped laminations secured to a bracket 27, said bracket having a projecting arm 28 secured by pins 29 to lugs 30 on the arms of lever 5. Armature member 26 is arranged to seal with pole faces 25^a and 25^b on field member 24 and the same is made

up of laminations secured to a lever 31. Lever 31 extends upwardly through yoke member 16 and is pivotally secured to said yoke member by a pin 32 as shown in Fig. 3, 5 and is also pivotally secured to lever 5 immediately above said yoke member by a pin 33.

From the foregoing it is apparent that 10 spring 13 serves to normally bias arms 4 and 5 towards each other to set brake shoes 2 and 3 against drum 1 and to normally hold armature member 26 in the position indicated by dotted lines. Upon energization of 15 winding 25, armature member 26 is attracted to the position shown in full lines and during such movement lever 31 acts through the medium of yoke member 16 and rod 15 to spread levers 4 and 5 apart against the action of spring 13 for release of the brake.

20 It should be noted that with the parts of the brake arranged as above described off centering of the drum 1 with respect to the brake levers 4 and 5 does not prevent sealing of armature 26 with the pole faces of field member 24, and that the range of movement of the armature can be readily varied by adjustment of rod 15 with respect to block 17. Furthermore it should be noted that 25 even though drum 1 is out of centered relation with respect to levers 4 and 5, said levers will adjust themselves to suit the position of the drum and will exert equal setting pressures on shoes 2 and 3 under the action of spring 13.

30 35 To equalize the releasing movement of

arms 4 and 5 webs 11 thereof are provided with adjustable stops 34 arranged to cooperate with fixed stops 35 on opposite ends of base 6. Ordinarily only one of the stops 34 is employed, the left hand stop being used 40 when the brake is mounted in a position wherein lever 5 tends to move by gravity towards the drum and the right hand stop being used when said lever tends to move by gravity in an opposite direction. 45

What I claim as new and desire to secure by Letters Patent is:

The combination with a brake drum, of a stationary supporting base to one side thereof, a pair of substantially parallel supporting arms pivoted to said base and arranged on opposite sides of said drum, brake shoes pivotally secured to said arms, a rigid link extending between said arms, said link being pivotally and adjustably connected at 50 one end thereof to the free end of one of said supporting arms, a brake operating member pivotally connected to said link and having one end thereof pivotally connected to the free end of the other of said supporting arms, an armature portion fixed to the free end of said operating member, an electromagnet including a field member fixed to said latter supporting arm and spring means associated with said link for effecting setting of said brake shoes. 55

In witness whereof, I have hereunto subscribed my name.

BERNHARD E. FERNOW, JR.
